UNITED STATES PATENT OFFICE

TIMOTHY B. POWERS, OF BROOKLYN, NEW YORK

CHAIR

Application filed September 15, 1928. Serial No. 306,242.

This invention has reference to a chair or stool, in which the seat member is rotatable on the base member, and further in which the seat is preferable adjustable for different heights above the floor.

The main object is to provide an improved form of rotatable chair, in which the base or floor support is without the usual feet or legs, that extend outwardly in several directions, and are objectionable in that they will be engaged by the feet of the user of the chair; and which chair also can be tilted on the edge or margin of the base plate, and then rolled on the floor to another location, and avoid the use of castors, and which will not mar or injure the floor or floor covering.

A further object is to provide a device of this character that is made of structural bars; and which also is adjustable for different elevations of the seat member.

In the accompanying drawings showing one embodiment of the invention:

Figure 1 is a side elevation.

Fig. 2 is a front elevation.

Fig. 3 shows the seat connection.

Fig. 4 is a view of the back connection.

Fig. 5 shows the floor member partly in section.

Fig. 6 is a detail of the notched bars of the seat member.

Fig. 7 shows the bent ear for the bail hinge connection.

Fig. 8 is a section on the line 8—8 of Fig. 7.

Fig. 9 is a detail of construction of the adjusting means for the foot rest.

The device as shown comprises essentially two members, a seat member, and a base or floor member, and which may be further provided with a back member, made adjustable if desired.

The seat member is shown as comprising a seat 2, that may be of wood, with a cross bar 1 secured at the front on the under side, and angle bars 3 and 4 are secured to the ends of the cross bar and extend downwards. At the rear of the seat is a cross bar 5 secured to its under face and fast to a supporting block at each end, as 6 and 6. Angle bars 8 and 9 are secured to these blocks and extend down

and are secured to the lower ends of the front bars 3 and 4 respectively.

The base member as shown comprises a circular base plate 10, that may be dished or concave slightly extending upward at the center, with a roll or bead 11 at the margins. An upright post 12 that may be a tube, is secured to project upwards at the center of the base plate, and may have a disc 13 with a hub 14 brazed to the lower end of the post, and secured to the base plate by rivets. The post 12 serves to rotatably support a frame that adjustably carries the seat member by the rear bars 8 and 9. A pair of angle bars 15 and 16 are secured to a cross angle plate 17 at their lower ends; and are also connected by an angle plate 18 at their upper parts, and are thus spaced apart parallel for such a distance as to slideably receive and support the said angle bars 8 and 9 of the seat member, as shown; which bars are preferably provided with adjustable means of securing them together. The upper angle plate 18 has one side or flange 19 extending horizontally and apertured at the middle part to receive a pin 20 on the top of the post 12 that projects through the hole 21 in the flange plate. The flange part 22 of the angle plate 17 also extends horizontally and has an opening 23 through which the post 12 passes whereby these two cross bars or plates are rotatably supported on the post and this frame of four members thus supports the seat member, that can rotate on the base plate and post. A fiber washer 24 is placed between the cross plate 19 and the top of the post 12, that will take all the weight of the chair. Also a fiber washer 25 may be secured to the lower plate 22 to engage the post, and these washers will not require oil and will not squeak as the chair is turned, as would a metal bearing.

To adjustably secure the sliding bars 8 and 9 of the seat member in the supporting bars 15 and 16 of the base member, I provide a bail 26, with bent ends 27 and 28 that are pivoted in ears 29 and 30 (Fig. 7), that are bent up from cut portions in the bars 15, 16. The seat bars 8 and 9 are provided with notches 33, 33, that will register successively with notches 31 and 32 formed in the bars 15 and 16.

16. The bail member near its ends will swing down into the registering notches on each side and thus lock the bars together in the adjusted positions; so that a considerable range of adjustment of elevation of the seat member is provided. It will be understood that in all of the positions of adjustment, the seat member can be rotated on the circular base plate. It will be obvious that there are no projecting legs or feet on the base of the chair, that might strike the feet of the user, especially if the chair is turned when in use; and that the base plate with the beaded edge or margin will not mar or injure any floor, and does not require castors. The chair can be tilted to an angle of about 45 degrees and then rolled on the edge of the disc base along the floor to another position in the room with great ease and not scratch the floor.

If desired a back member can be applied to the seat, and for this purpose the blocks 6 and 7 have slots 34, 34, in which slide bars 35, 35, that may be locked in adjusted positions by screws 36 in the blocks, that turn in threaded holes in the blocks that are angular to the bars. These bars 35 are connected at the tops by a cross rod 37. On each bar 35 is pivoted a plate 38 at its lower end below the upper end of the bar, and the upper ends of these plates are hinged to a flat back rest 40 at hinge plates 41 at each end of the rest. This plate 38 has three holes 43, that register successively with a hole 44 in the end of each bar 35, and a thumb screw 45 passes through the registering holes to lock the bars in adjusted positions. Headed studs 46, 47, on the bars 16, 16, engage the edges of the bars 8 and 9, that slide thereon and prevent displacement thereof.

If desired a foot rest may be attached at the lower part of the seat member that moves up and down, and which can be adjusted, and also readily removed. As shown a bar 50 is bent back at each end portion, 51, 52, and these ends enter blocks 53, 54, see Fig. 9. These blocks are secured to the blocks 3 and 4 by suitable means, and each have a channel portion 55, at one side of which is a threaded bore 56, that contains a bolt 57. This bolt when advanced will press the bars down into the channel and securely hold them in adjusted positions as shown.

What I claim is:—

1. In a chair, a seat member comprising a seat having an upright bar secured thereto on each side at the front, a supporting bar secured at the lower end of each said upright bars with their upper ends secured at the rear of the seat member, a base member comprising a pair of inclined angle bars, a cross angle plate connecting the upper parts of the latter bars with an apertured flange portion extending horizontally, a second cross angle plate connecting the lower ends of said

latter bars with a horizontal apertured flange, a flat dished base plate, an upright post secured to the base plate and having a journal bearing in said two apertured flange portions of the cross bars.

2. In a chair, a seat member comprising a seat having an upright bar secured thereto on each side at the front, a supporting bar secured at the lower end of each said upright bars with the upper ends secured at the rear of the seat member, a base member comprising a pair of inclined angle bars, a cross angle plate connecting the upper parts of the latter bars with an apertured flange portion extending horizontally, a second cross angle plate connecting the lower ends of said latter bars with a horizontal apertured flange, a flat dished base plate, an upright post secured to the base plate and having a journal bearing in said two apertured flange portions of the cross bars, said seat supporting bars being adjustably secured in said base member angle bars to hold the seat in different positions above the floor.

3. In a chair, a seat member comprising a seat having an upright bar secured thereto on each side at the front, an angle bar secured at the other end of each said upright bars and provided with notches in corresponding edges, said seat member at the rear being connected to the upper ends of the notched bars on each side, a floor member comprising a pair of notched bars including a base member carrying the latter notched bars secured thereto in position to have said seat member notched bars slide therein to bring the different notches into register, said floor member notched bars each having a slit portion bent out to form an ear, a bail member having its ends bent and pivoted in said ears to swing down into the said register notches to lock the seat member in adjusted positions on the floor member.

Signed at New York, N. Y., this 29th day of August, 1928.

TIMOTHY B. POWERS.
